Industries, Inc., Huntingdon, Pa., a corporation of
Pennsylvania

Filed Oct. 6, 1959, Ser. No. 57,833

Term of patent 14 years

(Cl. D55—1)

Figure 1 is a perspective view of a cycle adjuster for a road marking machine showing my new design, the broken line showing being for purposes of illustration only.

Figure 2 is a view in side elevation of the new design for cycle adjuster.

Figure 3 is a view similar to Figure 2 but showing the opposite side of the cycle adjuster.

Figure 4 is a rear end elevation of the design shown in Figure 2.

Figure 5 is a view similar to Figure 4 showing the front end elevation.

Figure 6 is a plan view of the design shown in Figure 2.

I claim:

The ornamental design for a cycle adjuster for a road marking machine, as shown and described.
